UNITED STATES PATENT OFFICE.

LA PORT W. HEEFNER, OF GREENSBURG, PENNSYLVANIA, ASSIGNOR TO PENNSYLVANIA RUBBER COMPANY, OF JEANNETTE, PENNSYLVANIA, A CORPORATION OF PENNSYLVANIA.

DESIGN FOR A VEHICLE TIRE.

Application filed December 3, 1927. Serial No. 24,376. Term of patent 14 years.

To all whom it may concern:

Be it known that I, LA PORT W. HEEFNER, a citizen of the United States, residing at Greensburg, in the county of Westmoreland and State of Pennsylvania, have invented a new, original, and ornamental Design for Vehicle Tires, of which the following is a specification, reference being had to the accompanying drawing, forming part thereof.

In the accompanying drawings Fig. I is a view in perspective of a vehicle tire showing my new design; Fig. II is a view of the tire in cross section; and Fig. III is a fragmentary view in perspective of the tire as seen on the mid-plane of the tread.

I claim:

The ornamental design for a vehicle tire, as shown.

LA PORT W. HEEFNER.
